UNITED STATES PATENT OFFICE.

MICHAEL SCHOLL, OF SAN FRANCISCO, CALIFORNIA.

CHIMNEY-CAP.

SPECIFICATION forming part of Letters Patent No. 293,526, dated February 12, 1884.

Application filed May 31, 1883. (No model.)

To all whom it may concern:

Be it known that I, MICHAEL SCHOLL, a citizen of the United States, residing at San Francisco, in the county of San Francisco and State of California, have invented a new and useful Chimney-Cap, of which the following is a specification.

The object of my invention is to provide a cheap and simple metal cap for chimney-pots in order to increase the draft of chimneys and render more certain the expulsion of smoke therefrom. I accomplish this object by the means illustrated in the accompanying drawings, in which—

15. Figure 1 is a perspective view of my improved chimney-cap. Fig. 2 is a plan view of the sheet of metal from which the cap is formed.

From a square sheet of iron or a sheet having four equal sides I cut with shears or otherwise stamp out four equilateral pieces to form the curvatures A A, and the four arms or points B B of the cap C. Each of the arms or points is perforated with one or more holes, 25 D, through the medium of which the cap is fastened to the stack or chimney-pot, and thus my cap-plate is formed and made ready to be applied.

In practice, the arms or points are bent downward, so as to form four semi-oval or truncated oval openings, F, of exact dimensions, while the body of the plate presents a flat or crown-like appearance, as shown in Fig. 1. It will thus be seen that the wind from all points of the compass will pass through the openings unobstructed and create a constant and equal draft in the chimney to which my device is attached at all times. The crown or cap is attached to the stack or chimney-pot

by rivets, pins, or screws E, and the openings 40 or draft-holes made larger or smaller by drawing down or raising up the cap or arms, and fastening through the upper or lower holes, as desired. If the connection is made to terra-cotta, the necessary holes are first drilled at 45 suitable distances around the upper end of the pipe.

My cap-plates may be cut from sheets of metal of different thicknesses, and made of different sizes to conform to chimney-pots or 50 stacks of greater or lesser diameters, and need not be bent up until wanted for use.

The sheets so formed and provided with holes or take-up slots may be multiplied in number and packed together one upon another 55 in bundles as flat sheets for use or for sale when wanted, thus occupying but little space.

Having thus described my invention, what I claim, and desire to secure by Letters Patent, is—

1. The metallic blank C, having four arms or points, B B, the sides of which are formed by the curvatures A A, substantially as described.

2. A chimney-cap composed of the metallic 65 blank C, having four perforated arms or points, B, with curved sides, said arms being bent down, as shown, and connected to the chimney pot or stack, whereby four truncated oval openings, F F, of equal dimensions are formed, 70 substantially as described.

In testimony that I claim the foregoing I have hereunto set my hand and seal.

MICHAEL SCHOLL. [L. S.]
